UNITED STATES PATENT OFFICE.

PRENTICE H. BOTTOMS, OF FRESNO, CALIFORNIA.

AUTOMATIC WATER-HEATER VALVE.

1,209,385.

Specification of Letters Patent. Patented Dec. 19, 1916.

Application filed March 29, 1916. Serial No. 87,601.

To all whom it may concern:

Be it known that I, PRENTICE H. BOTTOMS, citizen of the United States, residing at Fresno, in the county of Fresno and State of California, have invented certain new and useful Improvements in Automatic Water-Heater Valves, of which the following is a specification.

This invention relates to valves and more particularly to valves adapted for use in connection with what are familiarly known as instantaneous hot water heaters. Broadly speaking, in devices of this character there is provided an automatically operating valve controlled by the passage of water therethrough when a spigot is open to actuate a second valve in connection with the heating coil through which the water passes to turn on the gas and heat the coil whereby the water delivered out the spigot is of a desired temperature.

One of the objects of the present invention is to provide a simple and practical device of the above general character which will be inexpensive to manufacture.

A further object is to provide a device of the above general character having few parts not likely to get out of order and which will be reliable, efficient and more economical in use and operation.

A further object is to provide a valve of the above general character, the operation of which may be partially controlled by the manner in which the spigot is turned on, thereby to deliver either hot or cold water, as desired.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, there is shown in sectional elevation the complete device in its normal position.

Referring now to the drawings in detail, 5 denotes a member, preferably a brass casting having a relatively large chamber 6 and a smaller chamber 7 at one side thereof. An 60 inlet 8 is provided near the top of the chamber 6 and two outlets 10 and 11 connect the opposite side of said chamber with the chamber 7. Within the chamber 6 is a cylindrical piston 12 having a piston rod 13 65 extending downwardly through an opening in the bottom, which opening is provided with a suitable packing device 14, substantially as shown. Below this piston is indicated at 15 the heat controlling member 70 such as a gas burner, the burner and associated coil being of general well known construction and application and for which reasons, it is believed to be unnecessary to show the same in detail. These parts are 75 so positioned and arranged that as the piston moves downwardly, it will actuate the member 15 and turn on the gas or other heating means to heat the coil.

The piston 12 is of peculiar shape and is 80 provided with an upwardly extending flange 16 having an elongated opening 17 adapted to register with the inlet 8 in all positions. At the opposite side of the opening 17 is a smaller opening 18 communicating with the passage 10 in one position and the passage 11 in the lower position of the piston 12. A spring 20 is provided for holding the piston in its normally raised position, as shown. The upwardly projecting 85 flange 16 is also provided at one side intermediate the openings 17 and 18 with an elongated slot 21 adapted to be engaged by the end of a screw 22 threaded into the side wall of the chamber 6 adapted to prevent 90 rotation of the piston 12 and always maintaining the openings 17 and 18 in proper vertical alignment with respect to the inlet and outlet. A threaded cap 23 is provided for the chamber 6 to permit access thereto 95 when desired. The chamber 7 is also provided with a piston 25 at one side of which are a plurality of small openings 26 adapted to register with the passage 10. At the opposite side are other openings 27 adapted 100 to register with an outlet 28 which leads to the heating coil, not shown, and thence to the spigot 30. This piston 25 is provided with a small vertical opening or cut away portion 31 to permit water to flow through 105 the inlets 26 and out through the opening 27 and nozzle 31 to the passage 28 when the

spigot is turned very slowly without causing any material actuation movement of the piston 12. The piston 25 is also provided with a short piston rod or guiding member 32 about which is coiled a spiral spring 33 resting upon a screw cap 34 at the bottom of the chamber. A slot 35 is also provided in the upper part of the piston 25 engaged by a set screw 36 threaded into the outer wall of the chamber 7 to limit the up and down movement of the piston 25 and also to prevent relative rotation which would otherwise carry the openings or ports 26 and 27 out of alignment with the inlet and outlet.

Now, as above explained, one of the objects of the present invention is to provide a valve which will permit a full flow drawing either hot or cold water, as desired, according to the manner rather than the direction in which the spigot is actuated. If hot water is desired, the spigot is turned on quickly which will relieve the pressure in the system and particularly below the piston 12 and the head of water from the inlet 8 will force this piston downwardly, closing the outlet 10 at the upper part by reason of the upwardly extending flange until the opening 18 in the flange registers with the outlet 11. This permits a clear passage of the water through the chamber 6 to the heating coil and spigot. In the meantime, however, the lower end of the piston rod 13 has actuated the valve lever 15 to turn on the heating means or gas beneath the heating coil. If, on the other hand, a full flow of cold water is desired, or a small amount of hot water from a previous actuation of the device which still remains in the heating coil, the spigot is turned on slowly and the water passes from the inlet through the outlet 10 and ports 26 and 27 to the outlet 28 by means of the notch 31 which does not materially reduce the back pressure beneath the piston 12. There is, however, sufficient pressure above piston 25 to force it downwardly, thus closing the outlet 11 from the chamber 6 by the lower part of the piston. The main opening 26 is then in register with the passage 10, as shown in dotted lines and the opening 27 will register with the outlet 28. The spigot may then be turned farther and allow a substantial full head of water to pass through the device without actuating the piston 12, this being cut off from an effective back pressure action by the lower part of the piston 25, as above explained.

It will thus be seen that the present device will permit the drawing of either hot or cold water as desired and will also materially reduce the expense of operation, inasmuch as the gas is not turned on and wasted every time the spigot is turned on.

The construction is simple and practical and inexpensive and is believed to accom-

plish, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

I claim:

1. In a device of the character described, in combination, a heating means control, a spigot, a plurality of water passages leading to said spigot through said device and means controlled by the turning of said spigot to direct a full flow of water through either passageway and to actuate the heating means control or not, as desired. 80

2. In a device of the character described, in combination, a heating means control, a spigot, two water passages leading to said spigot, and means controlled by the manner of turning on said spigot to direct the water through either of said passageways to the exclusion of the other and to actuate the heating means control or not, as desired. 90

3. In a device of the character described, in combination, a heating means control, a spigot, two passageways leading to said spigot including separate chambers and pistons in said chambers controlled by the turning of said spigot to direct the water through either chamber to the exclusion of the other, thereby to actuate the heating means control or not, as desired. 100

4. In a device of the character described, in combination, a heating means control, a spigot, two water passageways leading to said spigot including chambers and spring actuated pistons constituting valves for closing and opening said passageways, said valves being adapted to be actuated by the manner in which said spigot is actuated to direct the water through either passageway and to actuate said heating means control or not, as desired. 105

5. In a device of the character described, heating means control, a spigot, two water passageways leading to said spigot including separate chambers, flanged pistons with in said chambers, springs for holding said pistons in normally raised position, ports in the flanges of said pistons communicating with the inlets and outlets of the passages whereby either piston is actuated according to the manner of turning on the spigot to actuate the heating means control or not, as desired. 120

6. In a device of the character described, heating means control, a spigot, two water 130

passageways leading to said spigot including separate chambers, flanged pistons within said chambers, springs for holding said pistons in normally raised position, ports in the flanges of said pistons communicating with the inlets and outlets of the passages, and means associated with the flanged pistons adapted to prevent relative rotation thereof with respect to the chambers, where-

by either piston is actuated according to the 10 manner of turning on the spigot to actuate the heating means control or not, as desired.

In testimony whereof I affix my signature in presence of two witnesses.

PRENTICE H. BOTTOMS.
